UNITED STATES PATENT OFFICE.

JOHN ALBERT LEE, OF BRIGHAM, UTAH.

CLIP-BOARD SHIELD.

1,138,979.

Specification of Letters Patent. Patented Mar. 30, 1915.

Application filed February 10, 1914. Serial No. 817,910.

To all whom it may concern:

Be it known that I, JOHN A. LEE, a citizen of the United States, and a resident of Brigham city, in the county of Boxelder and State of Utah, have invented a new and Improved Clip-Board Shield, of which the following is a full, clear, and exact description.

An object of my invention is to provide a transparent shield and covering adapted for attachment to a clip board, that is to say, to a base provided with a clip. By a clip board, it is to be understood, is meant any equivalent base having means to hold paper to be written upon.

The invention is particularly applicable to a clip board for holding a conductor's train book, or a yard checker's train sheet, or the like, while checking trains in the rain, snow, or wind, whereby the book or sheets will be protected from the weather, and at the same time will be in full view and may be conveniently written upon by the user of the device.

A further object of the invention is to provide a shield for the indicated purpose adapted to be either permanently or removably attached to the clip board.

The invention also has for its object to provide a means for lifting the spring clip from the exterior of the device.

The invention resides in the novel features characterizing the device and will be more particularly explained in the specific description following.

Reference is to be had to the accompanying drawings forming a part of this specification, in which similar characters of reference indicate corresponding parts in both views.

Figure 1 is a perspective view of my improved transparent shield showing the same applied to a clip-board; and Fig. 2 represents a longitudinal vertical section of the shield and clip board.

In carrying out my invention any suitable board or base 10 is utilized, desirably having a spring clip 11. A known form of clip illustrated is pivoted by ears 12 to the bottom member 14 by a hinge pin 13. The clip is shown also with a known form of stops 15, for properly positioning the train sheets 16, or a conductor's train book or the like. The spring of the clip is indicated by the numeral 17.

My improved shield is in the form of a hood 18, of flexible material, preferably mica or flexible celluloid, the said hood arching upwardly, being of a height to accommodate the user's hand beneath the top 18 when writing on the sheets or book 16. The head end of the hood adjacent to the clip is closed, having a transparent sheet 19 of the same material as the body, or equivalent material. The said hood is secured in the instance shown by producing a flange 19^a thereon, which is sewed or glued as at 20 to the adjacent edge of the body. The opposite end of the shield is open for the ready entrance and removal of the hand of the user. The bottom of the shield is also open and the side edges 18^a at the bottom are secured to the side edges of the board 10. The means for securing the said side edges, in the instance shown, consist of pins or nails 21.

In order to operate the clip 11 from the exterior of the shield and clip board, and raise the clip when desired against the tension of its spring 17, a device connected with the said clip and extending to the outside is provided. As here shown, eyes 22, 23, on the clip and bottom member 14 respectively are given a downward direction, and a strap 24 connects with the eye 22 of the clip and extends through the eye 23 of the bottom member 14, the free ends, in practice, being given a sufficient length to be taken hold of by the user. Thus a pull on the strap 24 or equivalent element will serve to raise the spring clip. The strap 24 extends, it will be seen, between the bottom of the head or closure 19 and the upper end of the clip board 10.

With the described device the clip board may be conveniently used out doors in inclement weather and will afford an unobstructed view of the book or sheet 16, while fully protecting the latter and permitting the ready entrance and removal of the user's hand beneath the shield.

It will be noticed that the clip member is located adjacent the closed end of the shield leaving a free and unobstructed entrance for the hand of the person using the device and providing means whereby the other hand of the operator can be readily used to manipulate the clip to release a pad or sheets when necessary. Furthermore by locating the clip member at this point it is shielded from the elements and protected against accidents and rust.

Having thus described my invention, I claim as new, and desire to secure by Letters Patent:

The combination with a clip board and its clip, of a transparent shield having transparent sides and top, the sides being secured to the clip board at their lower edges, a transparent closure for the head end of the board, the opposite end being open, said clip 10 secured to its board within the hood adjacent

its closed end, and a pull device connected with the clip and extending downwardly at the outside of the hood.

In testimony whereof I have signed my name to this specification in the presence of 15 two subscribing witnesses.

JOHN ALBERT LEE.
